UNITED STATES PATENT OFFICE.

GLEN RUSSELL BOOTH, OF CHANA, ILLINOIS.

LIFTING-JACK.

No. 867,786.

Specification of Letters Patent.

Patented Oct. 8, 1907.

Application filed July 5, 1907. Serial No. 382,378.

To all whom it may concern:

Be it known that I, GLEN RUSSELL BOOTH, a citizen of the United States, and a resident of Chana, in the county of Ogle and State of Illinois, have invented 5 new and useful Improvements in Lifting-Jacks, of which the following is a full, clear, and exact description.

This invention is an improvement in lifting jacks, the purpose of which is the provision of a comparatively 10 simple and practical jack, embodying a construction consisting of a base carrying a slotted standard in which is slidably mounted a lifting bar, the said bar having an adjustable load-supporting member on one side and provided with rack-teeth on its opposite side, which 15 are adapted to be engaged by the toothed inner end of an operating lever, the latter being pivotally and slidably supported in inclined slots formed in the slotted standard and operating to automatically disengage and reengage the teeth of the lifting-bar as the lever is reciprocated. The lifting-bar is automatically engaged 20 and held during the lifting of the load by a spring-pressed pawl, which is provided with a projection on its inner face adapted to be thrown into engagement with the said teeth by the operating lever, which action 25 disengages the pawl proper from the teeth of the lifting-bar and serves as a brake in lowering the load. The pawl is also constructed with projecting fingers at opposite sides for disengaging it from the lifting-bar by hand.

30 Reference is to be had to the accompanying drawings forming a part of this specification, in which similar characters of reference indicate corresponding parts in all the views.

Figure 1 is a side elevation of my improved jack complete; Fig. 2 is a central vertical section of the same; Fig. 3 is a plan of the jack; and Fig. 4 is a sectional view similar to Fig. 2 on an enlarged scale.

More specifically stated, the construction of the jack comprises a base 10 of suitable extent, which supports 35 a standard or frame 11, the latter being slotted substantially its entire length for receiving a slidable lifting-bar 12. The connection between the standard and base is strengthened by the radiating flanges or ribs 13, and the standard is strengthened internally by parallel 40 cleats 11^a, and externally by parallel cleats 11^b, as shown in Figs. 1 and 2.

As best shown in Fig. 3, the lifting-bar is of reduced thickness on its longitudinal center, which provides it with thickened heads at opposite sides, the edges of the 45 inner head being dove-tailed adjacent to the reduced central portion of the bar, as indicated at 14, which provides for the snug but free sliding engagement with the standard 11.

The outer head of the lifting-bar is provided on its 50 front face with rack-teeth 15 which are engaged by a load-supporting member or block 16, said block having

a tooth 17 at its lower end for this purpose, and constructed with straps 18 at its top which embrace the head of the bar 12 at opposite sides, as clearly shown in Fig. 3. This construction adapts the block to be adjusted longitudinally of the lifting-bar and engaged with any of the rack-teeth by tilting it slightly upward to disengage the tooth 17. In this way the block 16 may be moved directly into contact with the load to be lifted without the necessity of elevating or depressing 60 the lifting-bar for this purpose.

On the inner face or head of the lifting-bar 12 are formed rack-teeth 19 which are adapted to be engaged by the teeth of a segmental gear 20 formed on the inner end of an operating lever 21, the said lever being pivotally and slidably supported on the projecting ends of a pivot pin 22 which are in engagement with the downwardly and inwardly inclined slots 23, the said slots being formed in the sides of the standard 11 and arranged on a slight arc as shown. Also in normal engagement 70 with the rack-teeth 19 of the lifting-bar is a pawl 24 which is preferably pivotally supported in the slotted standard 11 above the lever, and is pressed in the direction of the lifting-bar by a spring 25, the latter being engaged with a projection on the rear face of the pawl 80 and seated within a recess formed in a lug 26, which connects the upper ends of the two portions of the standard 11, as clearly shown in Fig. 2.

The pawl 24 is constructed with a depending tail 27 which is provided on its inner face with a projection 85 or tooth 28 beveled at the top, as shown, and adapted when the pawl is thrown from engagement with the lifting-bar to itself engage the teeth and provide a brake when the load is lowered. This is accomplished automatically by throwing the operating lever 21 to 90 the dotted position shown in Fig. 2, which brings a projection or lug 29 formed on the lever into engagement with the enlarged extremity 30 of the pawl, forcing the same to the dotted position indicated. The pawl may also be disengaged from the teeth of the rack- 95 bar by hand, for which purpose fingers 31 project from the opposite sides thereof through slots 32 formed in the standard 11.

Over the slots 23 are arranged cap plates 33, as shown 100 in Figs. 1 and 3, and which serve as coverings to protect the gear 20 and prevent interference therewith during the effective working of the operating lever 21. The engagement of the beveled or dove-tailed edges of the lifting-bar 12 with the opposing edges of the standard 11, lessens the spreading pressure on the standard, 105 strengthens the jack as a whole, and also produces a binding or braking effect at that point. When pressure is put upon the operating lever 21, forcing the brake tooth 28 against the teeth of the lifting bar 12, the latter is forced directly against the dove-tailed 110 parts.

In operating the jack, the load is ordinarily brought

- to bear directly on the supporting block or member 16, or it may rest directly on the top of the lifting-bar, which, as shown, is scalloped out as indicated at 33° to prevent slipping and also to fit under the axle of a 5 wagon, carriage, automobile or other vehicle, thus avoiding any scratching of the same. On reciprocating the lever 21, its toothed inner end automatically slides upwardly in the slots 23 as the handle 21 is raised, and carries said teeth out of the path of the 10 rack-teeth 19. On, however, depressing the lever the toothed sector drops to the bottom of the slots 23 and engages the rack-teeth, causing the lifting-bar to move upwardly, the same being automatically engaged and held when the lever is being elevated by the pawl 24. 15 If it is desired to drop the load suddenly, the operating lever is carried upward to the dotted line position shown at the top of Fig. 2, and the jack is suddenly released, just enough pressure being applied to the lever 21 to release the pawl 24. When it is desired to apply 20 the brake, the operating lever 21 is forced inwardly with considerable pressure and the tooth 28 carried by the tail 27 of the pawl 24, is forced into contact with the teeth 19, thus breaking the fall of the jack. The jack may be released slowly by hand and under per- 25 fect control, by simply allowing the operating lever to drop downward engaging its teeth with those on the lifting-bar and then, on applying sufficient pressure on the operating lever to raise the lifting-bar in order to remove the pressure from the pawl, the pawl may be 30 released and held out of contact by the fingers, while the lever is allowed to rise, and at the same time the lifting-bar is lowered very carefully and under full control of said lever. The lifting-bar may be lowered to any desired distance by repeating the above operation. 35 The invention as shown and described while being the preferred practical construction of the jack, may be obviously modified in numerous minor particulars within the scope of the invention as defined in the annexed claims.
- 40 Having thus described my invention, I claim as new and desire to secure by Letters Patent:
1. In a lifting jack, a slotted standard, a lifting-bar slidably mounted within the slot of said standard having rack-teeth formed at one side thereof, said lifting-bar being reduced in thickness on its longitudinal center, forming thickened heads at opposite sides, the edges of the inner head being dove-tailed adjacent to the reduced central portion of said lifting-bar, an operating lever having a toothed inner end adapted to engage the teeth of the lifting-bar and pivotally supported in inclined slots formed in the standard, and a pawl pivoted to said standard adapted to automatically engage the teeth of the lifting-bar and support the same as the bar is elevated.
  2. In a lifting jack, a slotted standard, a lifting-bar 55 slidably mounted in the slot of said standard, having rack-teeth at one side thereof, an operating lever having a toothed inner end adapted to engage the teeth of said bar, having a depending tail provided with a braking-tooth adapted to be thrown into engagement with the teeth of said bar by the operating lever.
  3. In a lifting jack, a base supporting a slotted standard, a lifting-bar slidably mounted in the slot of said standard, having rack-teeth formed at one side thereof, said lifting-bar being scalloped out at its upper end, an operating lever having a toothed inner end pivotally and slidably supported in inclined slots formed in said standard and adapted to engage the teeth of the lifting-bar, and a pawl normally engaged with the teeth of said bar, having a depending tail provided with a braking-tooth or projection on its inner face adapted to be thrown into engagement with the teeth of the lifting-bar by the operating lever.
  4. In a lifting jack, a lifting-bar having rack-teeth, an operating lever having a toothed inner end adapted to engage the teeth of the rack-bar, a pawl adapted to automatically engage the teeth of the lifting-bar and support the same as the bar is elevated by the operating lever, said pawl having a depending tail provided with a braking-tooth adapted to be thrown into engagement with the teeth of the lifting-bar for the purpose described.
  5. In a lifting jack, a slotted standard, a lifting-bar slidably mounted within the slot of said standard, having rack-teeth formed at one side thereof, an operating lever having a toothed inner end adapted to engage the teeth of the lifting-bar, a pawl normally engaged with the teeth of said bar, having a depending tail provided with a braking-tooth adapted to be thrown into engagement with the teeth of the lifting-bar by the operating lever, and fingers projecting from the opposite sides of said pawl through slots formed in said standard for the purpose described.
  6. In a lifting jack, a standard, a lifting-bar slidably mounted on the standard, having rack-teeth formed at one side thereof, an operating lever having a toothed inner end adapted to engage the teeth of the lifting-bar, a spring-pressed pawl normally engaged with the teeth of the lifting-bar, having a depending tail provided with a braking-tooth, and a lug formed on the operating lever adapted to engage the said tail of the pawl and force said braking-tooth into engagement with the teeth of the lifting-bar for the purpose described.
  7. In a lifting jack, a standard, a lifting bar slidably mounted on the standard, having rack teeth formed at one side thereof, said lifting bar being reduced in thickness on its longitudinal center, forming thickened heads at opposite sides, the edges of the inner head being dove-tailed adjacent to the reduced central portion of said lifting-bar, an operating lever having a toothed inner end adapted to engage the teeth of the lifting-bar, a spring-pressed pawl normally engaged with the teeth of the lifting bar, having a depending tail provided with a braking-tooth, and a lug formed on the operating lever adapted to engage the said tail of the pawl and force said braking-tooth into engagement with the teeth of the lifting-bar for the purpose described.
- 105 In testimony whereof I have signed my name to this specification in the presence of two subscribing witnesses.
